Flick,

UNITED STATES PATENT OFFICE.

WILLIAM H. FRICK, OF PHILADELPHIA, PENNSYLVANIA.

REAMER.

1,241,953.

Specification of Letters Patent. Patented Oct. 2, 1917.

Application filed July 19, 1916, Serial No. 110,150. Renewed June 13, 1917. Serial No. 174,618.

To all whom it may concern:

Be it known that I, WILLIAM H. FRICK, a citizen of the United States, residing at Philadelphia, in the county of Philadelphia and State of Pennsylvania, have invented new and useful Improvements in Reamers, of which the following is a specification.

This invention relates to machinists' tools and particularly to devices employed for 10 truing and enlarging holes and commonly known as reamers.

The primary object of the invention is to provide a reamer having a series of rotatably adjustable cutters in the periphery thereof, and simple, reliable and efficient means for holding the cutters in position and adjusting them to regulate and vary their cutting action.

20 The invention consists of the features of construction, combination and arrangement of parts hereinafter fully described and claimed, reference being had to the accompanying drawing in which:—

25 Figure 1 is a vertical longitudinal section through a reamer constructed in accordance with my invention.

Fig. 2 is a front end elevation thereof.

Fig. 3 is a detail view of the adjusting 30 collar.

Referring to the drawing, 1 designates the body of a bit holder, cylindrical in form, having a reduced portion or neck 2 at the rear end, and furnished with a central bore 3 extending entirely through the holder, the said body being formed in its rear end with an annular flange or abutment shoulder 4.

The holder 1 is provided with a series of 40 channels or grooves 5, cylindrical in form, arranged concentrically to the axial line of the holder, and having one side open to the periphery of the holder.

These grooves extend to and through the 45 forward end of the body 1, but terminate at their rear ends in proximity to the flange or abutment 4.

Within the said channels or grooves 5 are located cylindrical cutting elements or 50 bits 6 each having a suitable longitudinal channel 7, so formed as to leave a salient lip 8 which forms the cutting edge of the bit. The cutting elements are held in their seats or channels 5 from lateral displacement by the overhanging of the curved walls 55 of said channels, and are retained from

longitudinal displacement by screws 9 which pass through holes in the flange or abutment 4 and are received in threaded sockets in the rear ends of the bits or cutters, it being 60 understood that by tightening the screws the bits may be locked in adjusted position, while by loosening the screws the bits will be freed for adjustment.

The bits have a turning fit in their seats 5 65 and when the said screws 9 are loosened the bits may be rotated in their sockets by the following means: The forward ends of the bits are formed with cam grooves 10, preferably in the nature of spiral grooves, which 70 receive the projections 11 upon an adjusting collar or ring 12, disposed between the forward ends of the cutters beyond the forward end of the body 1 and having an inwardly extending flange 13. The collar is 75 carried by an actuating member 14 which is in the form of a tube or thimble, which extends through the collar and has a flange 15 bearing against the outer side of the flange 13 and is provided with a nut 16 80 bearing against the inner side of said flange, whereby the collar is clamped to the tube or thimble. The tube or thimble is externally threaded to adjustably fit within the threaded forward portion 17 of the bore 3, 85 and is provided at its forward end with spanner receiving sockets or recesses 18 whereby said tube or thimble may be turned or rotated, with the effect of imparting a corresponding motion to the collar 12, from 90 which it will be seen that when the cutters are free for adjustment and the adjusting collar turned or rotated by means of the actuating tube or thimble the projections 11 engaging the spiral or cam slots 10 will 95 turn or rotate the cutters in one direction or the other for adjustment, adapting the cutters to be adjusted in a ready and convenient manner and then firmly locked in 100 adjusted position by the projections and cam grooves and through the tightening of the screws 9.

I claim:—

1. In a reamer, the combination of a holder, a series of rotatably adjustable 105 cutters upon the holder provided with cam grooves, and a longitudinally movable adjusting member having projections to engage said grooves, for rotatably adjusting the cutters.

2. In a reamer, the combination of a holder, a series of rotatably adjustable 110

cutters carried thereby, said cutters being provided with cam grooves, a longitudinally movable adjusting member having projections to engage said grooves, and an operating element for communicating motion to said rotatable adjusting member.

3. In a reamer, the combination of a holder, a series of rotatable adjustable cutters carried thereby, said cutters being provided with cam grooves, a longitudinally movable adjusting member having projections for engagement with said grooves, and means for locking the cutters in adjusted position.

10 4. In a reamer, the combination of a holder, a series of rotatably adjustable cutters carried thereby, said cutters being provided with cam grooves, an actuating member movably mounted on the holder, and a longitudinally movable adjusting member operated by said actuating member and having projections to engage said cam grooves.

15 5. In a reamer, the combination of a holder, a series of rotatably adjustable cutters carried thereby, said cutters being provided with cam grooves, a rotary adjusting member having projections engaging said cam grooves, and an actuating member connected with the holder for longitudinal adjustment relative thereto and operatively connected with said adjusting member.

20 6. In a reamer, the combination of a holder, a series of rotatably adjustable

25 cutters carried thereby, said cutters being provided with cam grooves, an operating member connected with the holder for movement longitudinally and rotatable with respect thereto, an adjusting member carried thereby and having projections to engage said cam grooves, and means independent of said actuating and operating members for locking the cutters in adjusted position.

30 7. In a reamer, the combination of a holder, a series of rotatably adjustable cutters carried thereby, said cutters being provided with cam grooves, an operating element connected with the holder for longitudinal and rotary movements with respect thereto, and an adjusting member carried by said operating member and having projections to engage the cam grooves in the cutters.

35 8. In a reamer, the combination of a holder provided with peripheral cutter seats, cutters rotatably mounted in said seats eccentric to the axis of the holder, said cutters being provided with grooves inclined to their axes, and a longitudinally movable member upon the holder provided with projections engaging said inclined grooves and forming therewith a cam mechanism for simultaneously rotating the cutters on their axes.

40 65 In testimony whereof I affix my signature.

WILLIAM H. FRICK.
